HENRY E. WARREN, OF ASHLAND, MASSACHUSETTS, ASSIGNOR TO WARREN CLOCK COMPANY, OF PORTLAND, MAINE, A CORPORATION OF MAINE.

MECHANISM FOR AUTOMATICALLY OPERATING TIMING MECHANISM.

1,251,946.

Specification of Letters Patent.

Patented Jan. 1, 1918.

Application filed March 30, 1914. Serial No. 828,117.

To all whom it may concern:

Be it known that HENRY E. WARREN, a citizen of the United States of America, residing at Ashland, in the county of Middlesex and Commonwealth of Massachusetts, has invented Improvements in Mechanism for Automatically Operating Timing Mechanism, of which the following is a specification.

- 10 This invention relates to mechanism for performing automatic repeated operations at predetermined time intervals, such as throwing an electric switch, operating valves, or performing other service of similar kind.
- 15 It consists in a timing apparatus, such as a spring-driven clock, an electric motor, a motor-controller therefor, consisting of adjustable devices operated by the clock to close and open the motor circuit through the
- 20 motor-controller at different predetermined intervals and to energize the motor so as to cause the automatic operation and at the same time wind the clock, and other means to cause the motor to open its own
- 25 circuit and reset the motor-controller after performing the functions mentioned.

A specific embodiment of my improvements is illustrated in the apparatus shown in the accompanying drawings, in which—

- 30 Figure 1 is a front elevation, and Fig. 2 a side elevation of a spring-driven clock with my improvements attached thereto;

Fig. 3 is an enlarged front view of a detail of the time dial, and a cross-section

35 of it;

Fig. 4 is a plan view of the same parts as in Fig. 3;

Fig. 5 is an enlarged view of the mechanism for automatically winding the spring

40 of the clock as hereinafter described.

Referring to the drawings, A represents an ordinary spring-driven clock, B a small electric motor, either direct or alternating current, and C is a snap-switch which opens

45 and closes an electric circuit supplying lamps *l'* or other appliances, when the stem *a* is rotated.

Reduced motion is transmitted from the motor B by means of the train of gears *b*, *c*, *d*, *d'*, *e*, *f*, *g*, to the stem *a* of the switch C, so that if the motor runs continuously the

switch would alternately be opened and closed at moderately timed intervals. Upon the same shaft with the gear *f* is loosely mounted the gear *h* which receives motion 55 from *f* through the friction-disks *i* and *k* which are held in compression against *h* by the spring-washer *l* and nut *m*, see Fig. 5; whereby *h* will rotate with *f* until the force to be transmitted is sufficient to cause the 60 disks *i* and *k* to slip upon the gear *h*. Gear *h* meshes with the gear *n* mounted upon the spring-winding shaft *o* of the clock. And to maintain the motion of the clock while the spring is being wound, one end of the 65 clock-spring is fastened to shaft *o*, and the other end of the spring to the driving-shaft *p*.

Driven by the clock through the pinion *q* mounted upon the hour hand sleeve, is a gear 70 *D* which, as shown, is intended to rotate once each week. Carried by the gear *D* is a dial *E*, graduated to days and hours. Mounted upon *E* are adjustable clips of two different kinds *r*, *r'*, and *s*, *s'*. These clips 75 have projections *r'* and *s'*, respectively, at different radial distances from the center of the dial *E*, and serve as electrical contacts.

Mounted upon a pivot *t* is a contact arm *u* carrying a flexible brush *u'*, which may be 80

called a contactor and which can be adjusted into the path of either of the series

of projecting contact pins *s'* or *r'*. The contactor arm *u* may be swung quickly out of

the path of one series of projecting contacts into the path of the other series by the

85 spring-controlled device consisting of the sliding rod *v*, spiral-spring *w* and the lever *x* attached to the pivot *t*. The arm *u* will be

maintained in the position shown in Fig. 1 90 until *v* has traveled far enough to the left,

for the spring *w* to exert its pull on the side of a straight line between *x* and *t*, opposite to that shown in Fig. 1, when the lever *x* and the arm *u* will be quickly thrown to the 95

position opposite to that shown, in which case the contactor *u'* will lie in the path of the projecting contacts *r'*. Axial sliding

motion is given to shaft *v* by an eccentric *y* mounted upon shaft *z* upon which, gear *f* is 100 made fast.

Current passes into the motor B from the

main conductor a' through the wire b' , thence through the motor field and armature and by way of the wire c' to the arm u , and its flexible contactor u' ; and then if the dial 5 E is in the proper position, through some of the projecting contact pins s' or r' into the metal parts of the mechanism and thence back to the line d' by means of the wire connection e' . The relation between the 10 number of teeth in the gears f and g is such that the eccentric y makes one-half a revolution every time the switch C is thrown into either its open or closed position, and the arm w is thrown to its opposite position by 15 the spring w , a little later than the switch C is thrown. Friction nut m is adjusted so that gear h will begin to slip at about the time when the spring of the timing mechanism is tightly wound.

20 The operation of this mechanism is as follows: The clips s and r are set at the respective times at which, for instance, it is desired to light and extinguish the lamps l' , l'' , for each day in the week, or several 25 times, if required, during the same day. When the time arrives for the lamps to be lighted, the dial E will have been rotated by the clock until a contact-pin s' touches the contactor u' , which will close the circuit and 30 the motor B will immediately begin to revolve and will soon throw the switch C so as light the lamps. Shortly afterward, by the movement of the cam y , the motor will open its own circuit by sliding the shaft 35 v to the left and thus throwing the contactor u , into the path of the contacts r' . In so doing the motor-circuit will be broken quickly so as to avoid arcing at the contactor u' . While the switch C is being thrown, 40 the clock will, of course, be wound by means of the friction-gear h , the relation between h and n being such as to wind the clock-spring f as much as it would be likely to run down between the average intervals of 45 operation of the switch. When the time arrives for the lamps to be extinguished, one of the contacts r' will be brought into touch with the contactor u' and the motor will again run sufficiently long to throw the 50 switch C , to wind the clock-spring f' and then to open its own circuit by throwing the arm u by reason of the movement of the rod v . It will be observed that with this improved device a large amount of power is 55 made available for the operation of a switch difficult to be moved, without impeding in any way the action of the clock and without requiring manual winding or other attention. For the purpose of facilitating the 60 setting of the lighting schedule the lighting contacts s have not only a circumferential adjustment on the dial E , but also a radial adjustment, so that the projecting contacts s' may, if desired, be located out of the

path of the contactor u' and thus omit to 65 light the lamps whenever this is desired, for example, on a holiday. This same mechanism can be used for other similar service, as for example, turning on and off gas lights, in which case the switch C would be replaced by a simple gas valve, and the motor B might then receive current from a battery.

I claim:

1. In mechanism for operating power controlling devices at predetermined intervals, 70 a time indicating apparatus, an individual motor therefor, a time graduated dial upon said indicating apparatus, electrical contacts carried thereby and adapted to be adjusted circumferentially and radially thereof, a circuit closer and an electric motor which prepares said closer to be engaged by said electrical contacts, and thereby supply energy to the motor at predetermined times.

2. In mechanism for automatically operating service apparatus at predetermined intervals, a timing device, a plurality of series of electric contacts given movement in a prescribed path by the timing device, a contactor projecting into the paths of the said series of contacts, a motor actuated by the contiguity of a contact and the contactor, service apparatus operated by the motor, means operated by the motor to open the 90 circuit established between a contact and the contactor and to stop the motor after completing the operation of the service apparatus and means to move the contactor into the path of another series of contacts 100 to prepare the mechanism for its next operation.

3. In mechanism for automatically operating service apparatus at predetermined intervals, a timing device, a plurality of series 105 of electric contacts given movement in a prescribed path by the timing device, a contactor adapted to be moved into the path of movement of either series of contacts, an electric circuit closed by the contiguity of 110 the contactor with one of said contacts, a motor in the circuit, service apparatus operated by the motor, means actuated by the motor to move the contactor from the path of one series of contacts to that of another, 115 and thereby stop the motor, and adjust the mechanism for a succeeding operation of the service apparatus.

4. In mechanism for automatically operating service apparatus at predetermined 120 intervals, a timing device, a plurality of series of electric contacts given movement in a prescribed path by the timing device, a single contactor adapted to be moved into the path of travel of either series of 1 contacts, an electric circuit closed by the contiguity of the contactor with one of said contacts, a motor in the circuit, service ap-

paratus operated by the motor, means actuated by the motor to move the contactor from the path of one series of contacts to that of another, and thereby stop the motor and adjust the mechanism for a succeeding operation of the service apparatus, and auxiliary mechanism for restoring energy to

the spring motor of the timing device, which is actuated by each operation of the electric motor.
